UNITED STATES PATENT OFFICE.

JOHN E. PREST, OF WORCESTER, MASSACHUSETTS.

THREAD-BOARD FOR SPINNING-FRAMES.

SPECIFICATION forming part of Letters Patent No. 758,933, dated May 3, 1904.

Application filed February 4, 1904. Serial No. 191,963. (No model.)

To all whom it may concern:

Be it known that I, JOHN E. PREST, a citizen of the United States, residing in Worcester, in the county of Worcester and State of Massachusetts, have invented certain new and useful Improvements in Thread-Boards for Spinning-Frames, of which the following is a specification.

This invention relates to a stop or means for holding the independent thread-boards in a substantially horizontal position, to the construction of the thread-guides with relation to the thread-boards, whereby the guides are prevented from turning or twisting, and to the mechanism for lifting or swinging up the thread-boards.

The nature of the invention is fully described in detail below and illustrated in the accompanying drawings, of which—

Figure 1 is a plan view illustrating my invention with the thread-boards in their normal horizontal position. Fig. 2 is an elevation showing the thread-boards in a raised position. Fig. 3 is an end view with the thread-boards down. Fig. 4 is a vertical section taken through one of the thread-boards when in a raised position. Fig. 5 is a section taken on line 5, Fig. 1. Fig. 6 is a view of the under side of one of the thread-boards, showing a modification. Fig. 7 is a section taken on line 7, Fig. 6. In Figs. 2 and 7 portions of the thread-guide guards are represented as broken out.

Similar letters of reference indicate corresponding parts.

Referring to the first five figures, *a* represents the roller-beam provided at the upper portion of its front side with the horizontal overhanging lip *b*. Supported by and having its bearings in suitable brackets *c* is a rotative rod or shaft *d*, preferably flattened longitudinally at *d'* to present a suitable surface for set-screws *e*, which secure the lifting-dogs on the shaft, said dogs each consisting of the hub or main portion *g* and oppositely-engaging portions *g'*. The shaft *d* is provided with a suitable handle or operating-lever *f*.

h h represent a series of independent thread-boards, preferably made of metal and having downwardly extending edges or flanges *h*.

These thread-boards are provided with sockets or tubular brackets *k*, through which the shaft *d* extends, and on which shaft the sockets and thread-boards freely swing.

n n represent the thread-guides extending through suitable openings *h''* in the front portions of the edges *h'* of the thread-boards, thence extending along and against the under side of the thread-boards, and with their inner ends *n'* bent at substantially right angles and parallel with the thread-boards. A trough-shaped cover or guard *p* is secured by suitable bolts and nuts *q r* to the under surface of each thread-board, said guard being shallow and with its central portion bearing against the under side of the thread-guide *n*, while the opposite sides or flanges *p'* of the guide bear, respectively, against one side of the thread-guide and the abutting end *n''* of said thread-guide, as illustrated in Fig. 2. The central or main portion, therefore, of the guard *p* holds the bent end *n'* in such a manner that the thread-guide cannot possibly rotate or turn, while the portions *p'* of the guide effectually prevent lateral movement. The thread-boards are lifted by means of the dogs *g g'*, which are rigid on the rotative shaft *d*. One dog may be located centrally under a thread-board, or it may be under the adjacent edges of two thread-boards, as indicated in Fig. 2, and when the boards are down the dogs are out of contact with the thread-boards, as indicated in Fig. 3, in which the nearest dog is shown below the flanges of the thread-boards, and the farthest dog (which is centrally under the thread-board) is shown below the body of the board. None of these dogs, therefore, act in any manner as stops, but are simply lifting devices.

When the thread-boards are down, they are all held in a nearly horizontal position by means of the overlapping lip *b*, which constitutes an integral stop for the thread-boards. In order that the leverage may not be too great, the thread-boards are fulcrumed or pivoted at quite a distance from the roller-beam by means of the comparatively long arms of the brackets *c*. Thus the thread-guides are prevented from turning or twisting, the thread-boards have their rear ends held down by a stop, which is common to all, and the thread-

boards are swung up by a rotative shaft provided with the lifting-dogs.

In the modification illustrated in Figs. 6 and 7 in place of the cover or guard p p' a cover or plate s , which corresponds to the portion p of the guard in the first five figures, is laid over the thread-board, its opposite edges resting on raised portions t integral with the thread-board and with the sockets thereon, said raised portions operating exactly like the portions p' , above described.

Having thus fully described my invention, what I claim, and desire to secure by Letters Patent, is—

- 15 1. In an apparatus of the character described, a roller-beam; a series of independent thread-boards pivotally supported in front of said roller-beam; and a lip extending outward horizontally from the roller-beam and longitudinally therewith over the rear ends of the series of thread-boards, whereby said ends are held down in line and the thread-boards in the series are held at an even height and in a substantially horizontal position.
- 20 2. In an apparatus of the character described, a roller-beam; a substantially horizontal rotative shaft supported by and in front of the roller-beam; a series of independent thread-boards supported loosely on said shaft; 30 a series of independent lifting-dogs rigid on the said shaft; a horizontal lip extending over

and along the rear edges of the series of independent lifting-dogs and holding them normally in line and in an approximately horizontal position; and means for rotating said shaft, whereby the independent lifting-dogs lift the independent thread-boards simultaneously out of the horizontal position in which they are normally held by said lip.

3. In an apparatus of the character described, the thread-board h provided with the downwardly-extending sides or flanges h' , the front flange being provided with a suitable opening h'' ; the trough-shaped guard p , p' secured to the under side of the thread-board, made longer than it is wide, and extending rearward centrally from the front edge of the thread-board; and the thread-guide n extending through said opening along and next to the inner surface of one of the sides p' of the guard and across and against the opposite side p' , between the guard and the under surface of the thread-board, for the purpose set forth.

In testimony whereof I have signed my name to this specification in the presence of two subscribing witnesses.

JOHN E. PREST.

Witnesses:

HENRY W. WILLIAMS,
A. K. HOOD.
